N. R. STROUT.
CARD GAME.
APPLICATION FILED JAN. 14, 1920.

1,399,823.

Patented Dec. 13, 1921.

2 SHEETS—SHEET 1.

Fig. 1.

Fig. 2.

Inventor

Noyes R. Strout

Percy H. Moore

Attorney

By

1,399,823.

N. R. STROUT.

CARD GAME.

APPLICATION FILED JAN. 14, 1920.

Patented Dec. 13, 1921.

2 SHEETS—SHEET 2.

Fig. 3.

Fig. 4.

Inventor

Noyes R. Strout

By

Perry H. Moore

Attorney

UNITED STATES PATENT OFFICE.

NOYES ROMUALD STROUT, OF NORWOOD, OHIO, ASSIGNOR TO THE CHAMPION AMUSEMENT COMPANY, OF CINCINNATI, OHIO.

CARD GAME

1,399,823.

Specification of Letters Patent. Patented Dec. 13, 1921.

Application filed January 14, 1920. Serial No. 351,408.

To all whom it may concern:

Be it known that I, NOYES ROMUALD STROUT, citizen of the United States of America, residing at Norwood, in the county of Hamilton and State of Ohio, have invented certain new and useful Improvements in Card Games, of which the following is a specification.

This invention has reference to improvements in playing cards and has for its principal object to provide playing cards simulating the game of outdoor baseball embodying cards naming various plays of the game as executed in the playing of same, which when played will afford considerable entertainment and interest for the players, the game being realistic and so played as to be exceedingly simple in its understanding.

It is also an object of the invention to provide a game of cards in which large or small numbers of persons may participate with equal interest, the picking of opposing sides or teams together with individual playing of each participant being possible with the same.

In order that the invention and the manner in which the same is played may be readily understood, I have in the accompanying illustrative drawings and the following detailed description based thereon, set out a preferred embodiment of the same.

In the drawings:

Figure 1 is a face view of the "base hit cards";

Fig. 2 is a similar view showing the "hit batter" and "base on error" cards;

Fig. 3 is a like view of the cards indicating the various "out" cards of the game, and

Fig. 4 is also a face view of the "strike" and "ball" cards.

In producing the card game forming my invention, I preferably include fifty-two cards in a pack or "deck" although, of course, the number may be varied, such as may be desired. These cards are divided into groups which are indicated as "One base hit", "Two base hit", "Three base hit", "Home run", "Hit batter", "Base on error", "Ground out", "Fly out", "Foul out", "Strike out", and "Ball". Various other cards simulating various plays which are made during the course of an actual game of base-ball, may be substituted for or added to the cards above mentioned should it be desired, although, it is believed that the "plays" named by these cards are such as will create no little interest and entertainment for players of the game.

The numbers of the differently designated cards of the game are such as will tend to maintain interest in the same and to prevent the lagging of this interest by its resemblance to the actual playing of base-ball. For example, but one "Home run" card is provided while the base hit cards are limited in number so as to prevent excessive appearance of the same during playing. So too, the remaining cards, with the exception of the "strike" and "ball" cards, which by reason of the number required to constitute an "out" or entitle a player to take position on first-base, are more plentiful in order that they will be drawn by the players more often during the progress of a game.

In playing the game, if a large number of persons are present, they are divided into sides or teams, each team appointing a pitcher. A scorekeeper may be also selected for keeping count of the runs and other plays made by the opposing teams.

The team to be first at the bat is determined whereupon the pitcher of the team presumably in the field thoroughly shuffles the cards and permits the first player on the opposing team to draw cards from the top of the now shuffled pack until he draws a base hit, base on balls, or strike out, etc., it of course, being understood that the drawing of three "strike" cards or four "balls" cards by a player constitutes an out or entitles him to position on first base, in accordance with the rules of the actual game of base-ball. The second man of the opposing team then is at the bat and draws from the card pack, and so on until three outs are made, whereupon the teams change their field and at bat positions and the cards are then held by the opposing pitcher for drawing by the second team now at the bat. The game is thus continued, score being kept by the appointed scorekeeper until a full game of nine innings or any decided number is played; the approved rules of base-ball governing throughout the game.

When the space permits and the number of people is large, the playing of the game may be made more interesting by preparing a home plate, a second and third base, the person at bat taking position at the home plate and then proceeding according to the play named upon the card drawn by him. Further, when but a small number of persons are present, a chart having the usual base-ball diamond thereon may be made and used.

What I claim is:

A base ball card game consisting of a deck of fifty-two cards, said cards being divided into groups, each of the cards of which bear legends characteristic to the actual game of base-ball consisting of the terms One base hit, Two base hit, Three base hit, Home run, Strike, Ball, Hit batter, Base on error, Ground out, Fly out, and Foul out, the groups of cards bearing the terms strike and ball being of such predominant numbers as to be sufficient, when compared with the number of cards in the remaining groups, to cause their being brought into play during the playing of the game with frequency sufficient to simulate the playing of the actual game of base-ball, and those cards bearing the remaining terms being of corresponding lesser numbers whereby they will be brought into play less frequently than the first mentioned group of cards, said cards of the various groups being adapted to be shuffled whereby to distribute the same throughout the deck for drawing therefrom.

In testimony whereof I affix my signature in presence of two witnesses.

NOYES ROMUALD STROUT.

Witnesses:

EVELYN BOHL,
LAIRY CRAIN.